UNITED STATES PATENT OFFICE.

MAYER M. SWAAB, JR., OF NEW YORK, N. Y., ASSIGNOR TO FRANK H. FLEER CORPORATION, OF PHILADELPHIA, PENNSYLVANIA, A CORPORATION OF DELAWARE.

DESIGN FOR CANDY-COATED CHEWING-GUM.

47,083.

Specification for Design.

Patented Mar. 9, 1915.

Application filed July 29, 1914. Serial No. 853,958. Term of patent 3½ years.

To all whom it may concern:

Be it known that I, MAYER M. SWAAB, Jr., a citizen of the United States, residing at New York city, in the county of New York and State of New York, have invented a new, original, and ornamental Design for Candy-Coated Chewing-Gum, of which the following is a specification, reference being had to the accompanying drawing, forming part thereof.

Figure 1 is a plan view of a candy coated chewing gum, showing my new design; and Fig. 2 is a side elevation of the same.

I claim:

The ornamental design for candy coated chewing gum, as shown.

MAYER M. SWAAB, JR.
